UNITED STATES PATENT OFFICE.

JAMES HUBER, OF PHILADELPHIA, PENNSYLVANIA, ASSIGNOR TO VICKERS LIMITED,
OF WESTMINSTER, ENGLAND.

AUTOMATIC BRAKE FOR SUBMARINE-MINE-ANCHOR CABLE-DRUMS.

1,314,659.

Specification of Letters Patent. Patented Sept. 2, 1919.

Application filed October 3, 1917. Serial No. 194,559.

To all whom it may concern:

Be it known that I, JAMES HUBER, a citizen of Switzerland, a resident of the city of Philadelphia, county of Philadelphia, and 5 State of Pennsylvania, have invented certain new and useful Improvements in Automatic Brakes for Submarine-Mine-Anchor Cable-Drums; and I do hereby declare the 10 following to be a full, clear, and exact description of the invention, such as will enable others skilled in the art to which it appertains to make and use the same.

This invention relates to an automatic brake for submarine mine anchor cable 15 drums.

When a submarine mine is launched from a vessel going at high speed, it will be carried into the wash of the propeller and unless some means is provided for controlling 20 the rotation of the cable drum, the cable will overrun itself and a snarling of the cable will result.

It is an object of the present invention to provide means for preventing the overrunning 25 of the cable and the consequent snarling of the same, especially when the mine is launched from a vessel going at high speed.

It is a further object of the invention to provide means which will control the paying 30 out of the cable as the anchor descends in the water.

These results are brought about broadly by providing means which will retard the 35 rotation of the cable drum with a force proportional to the force which tends to rotate the drum.

I have illustrated in the drawing one embodiment of the invention which, however, may be modified to a considerable extent and 40 still produce the results above set forth.

Figure 1 is a fragmental sectional view of a submarine mine, illustrating the invention applied to the mine anchor.

Fig. 2 is a fragmental elevation looking at 45 the ends of the brake arms, and

Fig. 3 is an enlarged detail of the end of one of the brake arms and a portion of the 50 brake drum.

In the drawing the mine is indicated by 55 the reference character 1, with which the mine anchor 2 is associated. This anchor includes the usual mooring cable drum 3 from which the mooring cable 4 extends. It is, of course, to be understood that, as the 60 anchor moves away from the mine, the

mooring cable unwinds from the cable drum 3, but the force which tends to rotate the cable drum naturally varies as the cable pays out from the same. For instance, when the drum contains three hundred feet of cable, the distance from the point where the cable begins to unwind to the center of the drum spindle is a predetermined amount. However, as the cable pays out from the drum this distance is gradually reduced and 65 consequently the leverage is reduced. As the cable unwinds from the drum the tendency of the drum will be to rotate at a greater rate of speed, obviously.

The end of the drum spindle 5 is provided 70 with flat faces, as at 6, and pivoted to this end by suitable means, such as a bolt 7, is a pair of brake arms 8. The number of these brake arms is not important as they may be increased or decreased at will. The 75 pivot of these arms extends transversely of the axis of rotation of the cable drum, so that upon the rotation of the cable drum the ends of the arms tends to move outwardly under the action of the centrifugal force de- 80 veloped and against the action of the spring, later described, so that the latter gradually loses its effectiveness.

The ends of these arms are somewhat enlarged to form, what I will term, brake 85 shoes, the faces 10 and 11 of which converge, as illustrated in Fig. 3 of the drawing. These arms are normally pulled together by suitable means, such as a spring 12, which is attached to eyes 13 on the arms so that the faces 10 and 11 of the shoe portions of the arms engage correspondingly shaped faces 14 and 15 on a brake drum 16. This brake drum is secured to the side of the mine anchor in the embodiment illus- 95 trated, is circular in form and has its center arranged in axial alignment with the spindle 5, so that upon the rotation of the cable drum and the consequent rotation of the brake arms 5, the faces 10 and 11 will 100 continuously contact with the faces 14 and 15 of the brake drum until the speed of rotation is such as to move the arms outwardly. It is to be understood that it is contemplated that the brake drum may be 105 secured to the anchor in various other locations and the brake arms may be associated with the cable drum in various other relations, the important requirement being that the brake drum be stationary with re- 110

lation to the cable drum and that the brake arms rotate with the cable drum. The face 11 of each of the shoes 9 is flat, as is also the corresponding face 15 of the brake drum 5 16. The face 10 of each of the shoes 9 is, however, curved, as illustrated in Fig. 3, the center of curvature being the center of the pivot 7 of the brake arms 8. The face 14 of the brake drum is likewise curved and 10 the center of curvature is the center of the aforesaid pivot 7. It will thus be seen that the concave face of each of the shoes 9 engages the corresponding convex face 14 of the brake drum, thus when the arms 8 move 15 outwardly against the action of the spring 12, the shoes will remain in contact with the face 14.

In order that there may be no jamming 20 of the brake shoes 9 so as to prevent the perfect contact of the faces of the shoes and the faces of the drum, the drum is provided with an annular recess 17 which is formed centrally of the drum so that the apex of each of the shoes will extend into the same.

25 When the cable begins to pay out from the drum, the greatest leverage is present and at this time the shoes are in engagement with the faces of the brake drum, and the spring 12 exerts its greatest force on the arms 8. As 30 the leverage decreases, the speed of rotation of the cable drum increases and the arms 8 move outwardly under the action of the centrifugal force developed against the tension of the spring 12, so the effectiveness of the latter is gradually reduced. However, as the 35 face 10 of each of the shoes remains in engagement with the face 14 of the brake drum, the shoes continue to act as a brake to the cable drum, but in view of the decreased 40 effectiveness of the spring 12, the pressure exerted by the shoes on the brake drum is naturally less so that the braking effect decreases in proportion to the decrease of the leverage or the decrease of the force tending 45 to rotate the cable drum.

While I have illustrated a particular embodiment of my invention, as has been stated, I contemplate various changes in the details of construction and therefore do not 50 wish to be limited to the particular embodiment shown.

What I claim is:

1. The combination with a submarine mine anchor including a cable drum, of means for 55 braking the cable drum with a decreasing

force bearing a predetermined ratio to the force tending to rotate the drum.

2. The combination with a submarine mine anchor including a cable drum, of a friction brake for controlling the speed of 60 rotation of the same with a force proportional to the decreasing force tending to rotate the drum.

3. The combination with a submarine mine anchor including a cable drum, of a 65 brake drum, an arm pivoted to the cable drum spindle and having a variable surface contact with the brake drum, whereby upon the pivotal movement of the arm the degree of said surface contact will be varied. 70

4. The combination with a submarine mine anchor including a cable drum, of a friction drum associated therewith, an arm pivoted to the cable drum spindle on an axis transverse of the same and having a portion engaging the brake drum, and resilient means 75 tending to hold the arm in engagement with the drum.

5. The combination with a submarine mine anchor including a cable drum, of a brake 80 drum stationary with relation to the cable drum, a brake arm pivoted to the cable drum spindle on an axis transversely of the latter and adapted to rotate therewith, said arm having a shoe on the end thereof arranged 85 to engage a face of the brake drum, the engaging faces of said shoe and brake drum being so disposed that upon the pivotal movement of the brake arm the shoe will move on the brake drum, and means tending 90 to maintain the shoe in contact with the face of the brake drum with varying pressure.

6. The combination with a submarine mine anchor including a cable drum, of a brake 95 arm pivoted to the cable drum spindle transversely thereof and having a shoe on its end, said shoe having one of its faces curved transversely, the center of curvature being the pivoted point of the arm, a brake 100 drum stationary with respect to the cable drum having a circular face co-axial with the cable drum spindle, said face being transversely curved, the center of curvature being the pivoted point of the brake arm, and 105 means tending to hold the curved face of the shoe in engagement with the curved face of the brake drum with varying pressure.

In testimony whereof I affix my signature.
JAMES HUBER.
